UNITED STATES PATENT OFFICE.

JAMES W. WEIR, OF FILLMORE, CALIFORNIA.

METHOD OF REFINING LUBRICATING-OIL STOCKS.

No Drawing.

Application filed May 14, 1925. Serial No. 30,357.

To all whom it may concern:

Be it known that I, JAMES W. WEIR, a citizen of the United States, residing at Fillmore, in the county of Ventura and State of California, have invented a new and useful Method of Refining Lubricating-Oil Stocks, of which the following is a specification.

This invention relates to a method of refining lubricating stocks from mineral or petroleum oils.

Lubricating oil stocks from mineral or petroleum oils are generally refined by treating the stocks with sulfuric acid followed by a removal of the acid sludge produced and a washing and neutralizing of the treated oil.

In my copending application Serial No. 545,538, filed March 21, 1921, which has been granted as Patent No. 1,564,501, there is described a method for treating lubricating oil stocks in which the stock, after an acid treatment and removal of the major portion of the sludge, is finished without the use of caustic soda through agitating the stock with a comminuted solid adsorbent material at a temperature at which the reaction products left in the oil decompose, and thus are caused to adhere to the comminuted sludge.

As pointed out in my copending application Serial No. 30,356, filed May 14, 1925, with certain classes of oils there is left in the oil subsequent to an acid treatment a certain amount of suspended acid sludge or "pepper" which is not always removed by the hot treatment with the comminuted solids unless an excessive quantity thereof is employed, and if not removed causes the oil to darken after standing. Said copending application described a method by which this class of acid sludge can be first removed from the acid treated stock prior to the treatment of the stock with a comminuted solid for removing the colloidally suspended reaction products therefrom.

When certain classes of lubricating oil stocks are treated by the improved method of said last mentioned copending application, there still may be present in the finished oil a quantity of sulfur compounds in various forms. These sulfur bodies, in addition to being detrimental to the lubricating value of the oil, will also cause it to darken and discolor upon standing for any appreciable length of time, thus impairing the appearance of the oil and decreasing its

market value. These sulfur compounds may be present in the original lubricating oil stock before acid treatment, or be possibly formed therein during such treatment. There is generally found, however, that lubricating oil stocks which have been subjected to a cracking reaction, tend to possess sulfur bodies most difficult to remove.

It is an object of the present invention to provide a method of treatment for refining lubricating oils which is adapted to remove part at least of these sulfur bodies or compounds from the oil, and thus to provide a process for forming an improved character of lubricating oil.

I have discovered that by a treatment of the lubricating oil stocks in a certain way with litharge or lead oxide (PbO) in connection with the removal of the colloidal soluble acid sludge with a comminuted solid adsorbent material, as in the process of my copending application Serial No. 545,538, which has been granted as Patent No. 1,564,501, the sulfur bodies or compounds may be removed therefrom, particularly when the oil has been subjected to a prior cracking operation.

The particular chemical reaction by which the litharge is able to remove these sulfur compounds and bodies during this stage of the treating process is not definitely known. The removal of the sulfur compounds may be accomplished through a chemical reaction resulting in the formation of lead sulfide or sulfate, or the sulfur compounds may be polymerized out of the acid stock by oxidation of the sulfur compounds, or they may be removed by a catalytic action of the lead oxide in the presence of the finely divided comminuted adsorbent material, and under the influence of heat. The litharge may be used in connection with or in combination with colloidal clays, fuller's earth or any other decolorizing agent where or whenever heat is employed during the treatment of a lubricating oil stock, for example, litharge may be used in the methods of treatment of lubricating oils described in patents issued to Chappell and Moore, Nos. 1,404,374 and 1,404,375, or similar methods.

The quantity of litharge added to the comminuted solid substance will depend entirely upon the grade of oil, with reference to objectionable sulfur content upon which it is to be used. Under ordinary conditions, the amount added to the comminuted solid

substance is approximately 1% to 5% by weight of the mixture.

The objects and advantages of the invention will best be understood from a description of a preferred example of a process embodying the invention, it being understood, however, that the process described is for the purpose of illustration, and details of operation may be widely varied for operating upon oils of different character, without departing from the spirit of this invention.

The lubricating oil stock is first treated with sulfuric acid in any usual or preferred manner, the sulfuric acid being added to the lubricating oil stock in one portion or in a plurality of separate portions, as desired, with an intermediate drawing off of sludge between each application. After the desired acid treatment, the mixture is allowed to settle and the major portion of the sludge or that portion of the sludge which will settle is then removed from the lubricating oil stock. There still remains in the lubricating oil stock two classes of acid sludge or reaction products, one portion being in the form of so-called "pepper" or finely divided solid sludge held mechanically suspended in the lubricating stock, and another form of sulfuric acid sludge held in a sort of colloidal suspension or solution in the stock. Preferably, the oil is then treated to remove this solid suspended sludge, for which purpose there is added to the lubricating oil, a quantity of comminuted solid adsorbent material to adsorb, gather or coagulate said sludge into sufficiently large particles of sufficient weight so that the same may settle to the bottom of the mass, where the same may be removed. The quantity of comminuted solid substance necessary to accomplish this purpose is generally about one ton of the solid substance to 30,000 gallons of lubricating oil stock to be treated, although it is to be understood that the amount may be varied with different lubricating oils.

The comminuted solid substance employed may be either comminuted granite, magnesium silicate, fuller's earth, diatomaceous earth, decolorizing agent made by acid treated montmorillonite, and like clay material, certain materials of the talc or serpentine group which may or may not have decolorizing properties.

After the oil is freed of said comminuted solid substance and the adsorbed, gathered or coagulated sludge the oil stock is then transferred to a suitable treating or mixing tank equipped with the proper mechanical apparatus for agitation and means for heating. A suitable required quantity of the finely divided comminuted solid adsorbent material is then added during agitation of the lubricating oil stock under treatment, the quantity generally being one ton of the solid

substance to 5,000 gallons of the lubricating oil stock. The solid here added, may, if desired, be merely a further application of solid similar to that added in the previous step of the process. During agitation of the mixture, or while maintaining the oil stock and solid commingled, the temperature of the mass under treatment is raised sufficiently (approximately 180° to 500° F., preferably 360° F.) to cause the remaining sludge in the lubricating oil stock to decompose.

The oil is held under heat until the sulfur dioxide products of the sludge decomposition have been substantially driven off. This treatment, may, if desired be aided by the passing of non-oxidizing gas through the mass being treated. Thereafter, preferably within a relatively short time and while the mixture is still under agitation, litharge is added in sufficient quantities to remove the objectionable sulfur compounds from the lubricating oil stock, the amount of litharge necessary being approximately 1% to 5% by weight of the comminuted solid adsorbent material which is employed. The agitation of the mixture with the added litharge is continued until reaction is completed, after which the adsorbed and combined compounds, with the comminuted adsorbent material and litharge, may be removed from the lubricating oil stock by settling, centrifugal force, filtration through filter blankets with a filter press, or by any well known means of separating solids or semi-solids from liquids. Subsequently, the oil may be brightened by being blown with air in the usual manner, and is preferably thereafter reduced in temperature, although it is not essential to provide apparatus or methods for quickly cooling the oil.

Any trace of foreign substance left remaining in the oil after the brightening operation may be removed by passing the same through a filter or strainer of material such as fuller's earth of approximately from 30 to 60 mesh.

By the method above described, such acid sludge or acid reaction products are removed by adsorption with comminuted solid materials with substantially no chemical reaction, and objectionable sulfur bodies are removed by litharge. Thus the oil is purified without injurious compounds being formed which remain in the oil after treatment or must be removed by further processing.

It is pointed out that the treatment herein described involving the use of litharge is not adapted in all cases for removing of all the sulfur compounds or bodies from the oil, but that in certain classes of lubricating oil stocks, particularly those having been subjected to a cracking reaction, a substantial reduction in the sulfur content is hereby effected.

While the process has been described in detail, it is understood that this is merely for the purpose of illustrating a practical embodiment of the process, and that various modifications may be made in the process without departing from the spirit of the invention, and the invention is therefore of the scope of the appended claims.

I claim:

- 10 1. A method of refining lubricating oil stocks which comprises treating the oil with sulfuric acid, settling and removing the settled sludge, then adding comminuted solid adsorbent material and agitating the same in the oil at a temperature below the decomposing temperature of the sludge or acid reaction products of the oil, separating the adsorbent material with the sludge thus gathered from the oil stock, then adding 15 comminuted solid adsorbent material to the oil stock and heating the mixture to a temperature sufficient to decompose the remaining sludge, and liberating sulfur dioxide therefrom, then adding litharge to the mixture, and separating the purified oil stock from the remainder of the admixture.
- 20 2. The method of refining a lubricating oil stock, which comprises treating the oil with sulfuric acid, settling and removing the major portion of the sludge, then agitating the stock with comminuted adsorbent material at a temperature below the decomposing temperature of the sludge, separating the adsorbent material with the mass adsorbed thereon from the oil stock, then agitating the oil stock with comminuted solid adsorbent material at a temperature not less

than 180° F. to decompose the remaining sludge and liberate the sulfur dioxide therefrom, then adding litharge to the mixture 40 to remove objectionable sulfur compounds from the oil stock, and separating the purified oil stock from the admixture.

3. The method of refining lubricating oil stocks, which comprises treating the oil with sulfuric acid, settling and removing the major portion of the sludge, agitating the stock with comminuted adsorbent material at a temperature below 180° F., separating the adsorbent material with the sludge gathered thereby from the oil stock, then agitating the oil stock with comminuted solid adsorbent material at a temperature sufficient to decompose the remaining sludge and liberate 55 sulfur dioxide therefrom, then agitating the mass with litharge to remove the objectionable sulfur compounds from the oil stock, blowing the mixture with a non-oxidizing gas during said treatment, and separating the purified oil stock from the admixture. 60

4. A method of refining lubricating oil stocks, which comprises treating the oil with sulfuric acid, settling and removing the major portion of the sludge, treating the oil stock with comminuted solid adsorbent material at a temperature sufficient to decompose the sludge present and liberate sulfur dioxide therefrom, then adding litharge to the mixture, and thereafter separating the oil stock from the admixture. 70

Signed at Los Angeles, California, this 7th day of May 1925.

JAMES W. WEIR.
